UNITED STATES PATENT OFFICE.

HARRY ASHLEY WIER, OF DALLAS, TEXAS.

VAPOR TOWER.

Application filed February 2, 1926. Serial No. 85,600.

My present invention has reference to a vapor tower which embodies a method and means for condensing and purifying high volatile vapors.

5 For a full and comprehensive understanding of my improvement reference is to be had to the accompanying drawings which form part of this specification.

In the drawings:

10 Figure 1 is a side elevation of my improvement.

Figure 2 is an enlarged central transverse sectional view through the tower.

Referring now to the drawings in detail, 15 the numeral 1 designates the dome of a still.

The oil vapors from the still find an outlet through a vapor-line pipe 2 connected to the dome. The longitudinal pipe of the vapor line is arranged at an upward inclination 20 and is coupled to a depending vertical pipe which in turn is coupled to a short pipe that enters the tower 3. This pipe is in turn coupled to a vertically arranged pipe 4 that is disposed centrally in the tower 3. Thus

25 the vapors are directed into the tower and are trapped in a sleeve 5 that surrounds the pipe 4. The sleeve has a closed upper end, and its lower and open end is welded or otherwise secured to a perforated baffle plate 6 which preferably has a flanged periphery that is fixed to the inner wall of the tower at a suitable distance from the bottom thereof. The baffle plate or disc 6 serves as a support for the sleeve 5.

30 The vapors are transmitted upwardly through the spaced convolutions of the conical portions 7 of a tube 8. In the showing of the drawings the conical portions of the tube 8 are seven in number, but, of course, 40 the tube 8 may have its convolutions gradually widened to provide any desired number of spaced conical portions. The conical portions 7 provide receptacles or baskets in which there may be placed a suitable absorbent agent 10, such as porous rock, iron ore, charred coal or any like agent which will act as a scrubber, desulphurizer, deodorizer, purifier, and catalytic, whereby the impurities and foreign matter will be absorbed as the vapors are transmitted through such agent.

45 The multiple coiled tube may be used as a heat exchanger by pumping oil into said tube at the top of the tower, where the end 55 11 of the said tube enters and the forcing of such oil through the end tube to the bot-

tom of the tower and thence upwardly through the lower straight branch 12 of the tube, its vertical extensions 13 and its horizontal extensions 14 through the outlet end 15 at the top of the tower. The horizontal portions 14 of the tube are arranged respectively over each of the conical coils or pocket portions of the said tube. The portions 14 aid as supports for filters 9. The filters - preferably - comprise basket-like screens in which are received several layers of steel shavings, mesh wire, steel wool or other suitable material which acts as a retarding agent and catalytic. The oil is further forced through the downwardly extending tubular member 16 which is coupled to a pipe 17 that has its passage controlled by a valve 18, the portion of the tube below the said pipe 17, being also controlled by a valve 19. This valve 19 is closed and the valve 18 is opened so that the oil will flow into the still, or the same may be directed into a storage tank by closing the valve 18 and opening the valve 19.

50 By a method and means as above set forth it will be noted that the oil pumped into the coil through its end 11, constitutes a cooling medium which is transmitted downwardly and comes into contact with the hot vapors 55 in an upward trend, thereby absorbing such heat as may be consistent with the cooling oil passing therethrough and further condensing such high boiling point hydro-carbon vapors in proportion to such volume of 60 cold oil put through said tube, thereby causing a distinct separation of the high boiling point vapors from that of the low boiling point vapors. This causes the low boiling point vapors to continue their ascension free 65 of a portion, at least, of such heavy impurities and foreign matters that are of low volatile nature and such portions carried back with the condensate of the high boiling point hydro-carbon vapors to the point of 70 exit in the bottom of the tower 3. This is accomplished by providing the bottom of the tower with a pipe 20 coupled to a horizontal pipe 21 that leads to the still. The passage through the pipe 21 is controlled by 75 valves 22 and 23, respectively. The condensate may be converted into an absorbent agent by closing the valve 23 and opening the valve 22, closing valve 30 and valve 29 and thus directing the condensate into an 80 arched by-pass 24 that is coupled to the pipe 21. The condensate passes through the by-

pass into the still, thereby raising the liquid level of condensate in the side of the tower to a point well above the perforated baffle plate 6, and through this liquid all vapors from the capped sleeve 5 are forced. The accumulated liquids or condensate will thus act as a purifier, absorbent, and as a deodorizer, causing the low volatile vapors to condense and return to the still through the arched bypass 24 for redistillation, thereby separating and scrubbing the high volatile vapors and freeing such vapors from a large per cent of impurities and foreign matters contained therein and which have a tendency to produce a low quality product. The highly volatile vapors being freed from foreign matters and impurities are transmitted upwardly with greater dispatch, since they are relieved of high boiling point hydrocarbons, by reason of the condensation produced by vapors coming into contact with said liquids in the bottom of the tower. The highly volatile vapors pass upwardly into the top of the tower and out through a vapor line 25 into condenser coils 26 and from such coils to the run down tanks.

With the employment of my improved tower, the cost of manufacturing gasoline and light oils is greatly reduced as with my improvement the employment of sulphuric acid, caustic soda and other such expensive chemicals generally required in the treatment of gasoline and light oils is entirely eliminated.

Further with my improvement a great reduction in the cost of equipment is obtained as the use of the vapor tower eliminates the expense required in building and fabricating a heat exchanger, and therefore the tower answers a two-fold purpose, as the crude oil or charging stock is charged to the stills through the conical or basket portions of the tube in continuous process of operation and the charging stock is then brought to a high temperature which makes for saving in fuel oil and in time, inasmuch as very little additional heat is required to bring the charging stock to a temperature of vaporization.

A gage 27 is arranged on one side of the tower between the bottom thereof and the lower filtering screen 9 so that the level of the liquid in the tower may be at all times ascertained. The top 28 of the tower is removable, the same being bolted to a flange on the tower, there being a vapor proof gasket ring between the flanged top of the tower.

The pipe 20, at a point below the pipe 21, has its passage controlled by a hand operated valve 29. The pipe 21 also communicates with the pipe 25, and this portion of the said pipe 21 has its passage controlled by a valve 30.

Having described the invention, I claim:

1. In an apparatus for the purpose set

forth, a vapor tower, means for directing vapor into the bottom of the tower, means in the tower for directing the vapor first in an upward direction therein, then in a downward direction, and then in a further upward direction to the top of the tower, means for subjecting the vapor in its last mentioned course, to a scrubbing and a catalytic action, means for filtering the vapor in its last mentioned course, means for subjecting the vapor to the action of a cooling agent in its last mentioned course and means for directing the purified vapor from the tower.

2. In an apparatus for the purpose set forth, a vapor tower, means for directing the vapor into the bottom of the tower, means in the tower for directing the vapor first in an upward direction therein, then in a downward direction, and then in a further upward direction to the top of the tower, means for subjecting the vapor in its last mentioned course to a scrubbing and a catalytic action, means for filtering the vapor in its last mentioned course, means for subjecting the vapor to the action of a cooling agent in its last mentioned course, means for directing the purified vapor from the tower, means for directing the condensate from the vapors out of the tower and means for maintaining a level of condensate in said tower so as to cause the condensate to serve as an absorbent agent for the vapors to separate from the vapors of low boiling point those of high boiling point, and means for directing the vapors from the tower.

3. In an apparatus for the purpose set forth, a vapor tower, a vapor conducting pipe entering the lower portion of the tower and extending upwardly in the center of the tower, a capped sleeve in the tower surrounding but spaced from the said vapor conducting pipe, a screen baffle in the tower providing a support for the lower end of the sleeve and said baffle being disposed above the bottom of the tower, said tower having spaced filtering mediums and having a combined absorbing agent, desulphurizer, deodorizer and catalytic therein below each of the filtering mediums, a tube in the tower and having spaced conical portions which serve as baskets for the desulphurizer, deodorizer and catalytic agent, means for admitting cooled oil into the tube and for directing the same through the top of the tower, valve controlled means for directing condensate from the bottom of the tower, and valve controlled means for conducting the vapors from the top of the tower.

4. In an apparatus for the purpose set forth, a vapor tower, a vapor conducting pipe entering the bottom of the tower and having a vertical branch that is arranged in the tower, a capped sleeve surrounding the last mentioned branch of the pipe but spaced therefrom, a perforated baffle plate in the

tower providing a support for the open bottom of the sleeve, a valve controlled pipe at the bottom of the tower, a valve controlled pipe at the top of the tower, an oil conductor tube comprising a continuous member having inlet and outlet branches arranged at the top of the tower, and having oppositely disposed vertical branches arranged at the sides of the tower and horizontal branches connecting said vertical branches, the lowermost

of said horizontal branches merging into a coil which is arranged around the sleeve, said coil throughout the length thereof and below the respective horizontal branches having conical coils providing baskets for a scrubbing agent, and the horizontal branches of the tube aiding as supports for filters.

15 In testimony whereof I affix my signature.

HARRY ASHLEY WIER.
